UNITED STATES PATENT OFFICE.

JOHN B. BOUCHARD, JR., OF OLDTOWN, MAINE.

RAILROAD-TIE.

1,259,827.

Specification of Letters Patent. Patented Mar. 19, 1918.

Application filed January 3, 1918. Serial No. 210,185.

To all whom it may concern:

Be it known that I, JOHN B. BOUCHARD, Jr., a citizen of the United States, residing at Oldtown, in the county of Penobscot and

5 State of Maine, have invented certain new and useful Improvements in Railroad-Ties, of which the following is a specification.

This invention relates to railroad ties, particularly to those of the combined metal and 10 wood type, and has for its object the provision of a railroad tie formed of a pair of similar castings connected by iron pipes, each casting being provided with a wooden block upon which the rail is secured.

15 An important object is the provision of novel means for securing the rails upon the blocks so constructed and arranged that they may be slid longitudinally of the blocks for permitting ready removal of the rails.

20 A further object is the provision of a tie of this character which will be comparatively simple and inexpensive in manufacture, durable in service, and efficient in use.

With these and other objects and advantages in view, the invention consists in the 25 novel features of construction and arrangement hereinafter more fully described and claimed and illustrated in the accompanying drawings, in which:

30 Figure 1 is a cross-sectional view through a railroad track showing the tie in side elevation,

Fig. 2 is a side elevation on a larger scale of a rail supporting member,

35 Fig. 3 is a top plan view thereof,

Fig. 4 is a cross-sectional view on the line 4—4 of Fig. 3,

Fig. 5 is a vertical longitudinal sectional view,

40 Fig. 6 is a horizontal longitudinal sectional view on the line 6—6 of Fig. 2.

Fig. 7 is a similar view on the line 7—7 of Fig. 2, and

Fig. 8 is a cross-sectional view on the line 45 8—8 of Fig. 7.

Referring more particularly to the drawings, the numeral 10 designates the tie as a whole which is composed of the castings 11 connected by a plurality of tubular members 50 or pipes 12 and 13. The tie thus formed is embedded in the road bed or ballast to a desired or suitable depth.

Each casting 11 is provided at its lower portion with outer bores or channels 14 extending entirely therethrough and an intermediate bore or channel 15 terminating

short of the outer end of the casting for providing an abutment 16. The pipe 13 is disposed within the channels 15 of a pair of castings with its ends engaging the abutments 16 for preventing relative inward displacement of the castings. The pipes 12 are disposed in the channels 14 and have their projecting ends threaded for engagement with jaw nuts 17 whereby relative outward movement of the castings is prevented. The ends of the pipes 12 may be closed by suitable caps or plugs to exclude water, if desired or advisable.

Each casting is formed at its ends with upstanding portions 18 recessed in their confronting faces as shown at 19 to provide overhanging retaining flanges 20 and 21. A block 22 of wood is associated with each casting and is retained in position by these 75 flanges. In order to secure the block firmly in place I provide spikes 23 passing through slots 24 in the flanges 20 and into the blocks.

In order to secure the rails in place upon the tie, I provide plates 26 disposed upon the blocks 22 and having their opposing ends bent to conform to the base of the rail as at 27. These plates are adjustable longitudinally of the blocks and are retained in position thereon by yokes 28 engaging upon the tops of the plates between the bent ends 27 and the upturned portions 29. The yokes are slideable longitudinally of the blocks and have their lower ends 30 bent inwardly and disposed within longitudinal grooves 31 in the sides of the blocks. After the rails have been properly positioned upon the blocks 22 the plates 26 together with the yokes 28 are slid along the tops of the blocks until the ends 27 engage 90 the bases of the rails. When the plates are in proper position spikes 32 are driven through holes 33 therein and into the blocks. To remove the rail, the spikes 32 are drawn out and the plates 26 together with the 100 yokes 28 moved outwardly away from each other until the ends 27 are out of engagement with the rail. It is of course understood that the plates 26 and yokes 28 are placed in position upon the blocks before 105 the blocks are secured within the castings.

From the foregoing description and a study of the drawings it will be apparent that I have provided a railroad tie which is comparatively simple and inexpensive and which provides for ready attachment or removal of the rail.

It will be understood that I reserve the right to make such changes in the form, construction and arrangement of parts as will not depart from the spirit of the invention or the scope of the subjoined claims.

Having thus described my invention, I claim:

1. A railroad tie comprising a pair of castings provided with bores extending entirely therethrough, tubular members extending through said bores, nuts on the ends of said members preventing relative separation of said castings, said castings being further provided with bores between said first named bores and terminating short of the outer ends of the castings, tubular spacing members disposed within said second named bores and abutting against the ends thereof for preventing relative inward movement of said castings, and rail securing means carried by each casting.
2. A railroad tie comprising a pair of spaced metallic members, upstanding portions on the ends of each member, a wooden block disposed and secured between said portions, said block being adapted to support a rail, rail engaging plates disposed upon said block and adjustable longitudi-

nally thereon, and a retaining member permanently engaging each plate and slidably engaging said block.

3. A railroad tie comprising a pair of metallic members secured in spaced relation, upstanding end portions formed integrally on each of said metallic members and having flanges overhanging inwardly toward each other at their upper edges and at one side edge defining a recess, a block disposed within said recess, a securing member passing through a slot in each of said upper flanges into said block, a pair of plates disposed upon the top of each block and having one end bent to conform to and engage the base of the rail and having an upwardly bent portion spaced from said end, and a yoke disposed between said bent portions of each plate, straddling said block and having its ends extending downwardly and bent inwardly to extend within longitudinal grooves in the sides of said block, whereby said plates and said yokes are together longitudinally adjustable of the block.

In testimony whereof I hereto affix my signature.

JOHN B. BOUCHARD, Jr.
